(57) CLAIM

The ornamental design for a brake pad, as shown and described.

DESCRIPTION

The brake pad is used in a centrifugal braking device to impede the circular motion of a spinning device.

FIG. 1 is a perspective view of the top and one complete side of a brake pad showing my new design;

FIG. 2 is a perspective view of the top and complete opposite side of the brake pad thereof;

FIG. 3 is a perspective view of FIG. 2 in the opposite degree of direction;

FIG. 4 is a top view of the brake pad embodying the design; and,

FIG. 5 is a bottom view of the brake pad embodying the design.
